UNITED STATES PATENT OFFICE.

HARRIET HILL, OF NEW YORK, N. Y., ASSIGNOR TO PAPER UTILITIES CORPORATION, A CORPORATION OF NEW YORK.

PAPER-VESSEL-MAKING MACHINERY.

1,314,192.

Specification of Letters Patent. Patented Aug. 26, 1919.

Application filed November 11, 1918. Serial No. 261,967.

To all whom it may concern:

Be it known that I, HARRIET HILL, a citizen of the United States, and a resident of the city, county, and State of New York, 5 (whose post-office address is 329 Lexington avenue, New York city,) have invented a new and useful Improvement in Paper-Vessel-Making Machinery, of which the following is a specification.

10 The object of my invention is to provide a suitable machine for turning out paper bowls and similar paper articles which are made from a circular blank by means of a plunger which is pressed through a suitable 15 die and attendant mechanism. This and other objects are accomplished by my invention, one embodiment of which is hereinafter more particularly set forth.

For a more detailed description of my invention, reference is to be had to the accompanying drawings, forming a part hereof, in which:

Figure 1 is a plan view of my improved machine.

25 Fig. 2 is an enlarged elevation of a portion of the same.

Fig. 3 is a side elevation opposite the side shown in Fig. 2, the scale being the same as in Fig. 1.

30 Fig. 4 is a sectional view showing a cam on the main shaft and attendant mechanism.

Fig. 5 is a sectional view taken on the line 5—5 of Fig. 2, looking in the direction of the arrows.

35 Fig. 6 is a sectional view through the die and plunger, which section is also taken on the line 6—6 of Fig. 5, looking in the direction of the arrows.

Fig. 7 is another sectional view taken substantially on the line 6—6 of Fig. 5, looking in the direction of the arrows, but more extensive than Fig. 6 and shows the plunger in a different position.

45 Fig. 8 is a sectional view showing the feed rollers in a different position from that occupied by them in Fig. 7.

Figs. 9 and 10 are fragmentary views showing a plan and side elevation, respectively, of the vessel made by this machine.

50 Throughout the various views of the drawings, similar reference characters designate similar parts.

My improved vessel making machine 1 is provided with a suitable base 2 from which 55 rise suitable supports for the various ele-

ments of the machine. At one end are located suitable pedestals 3 which carry the main shaft 4 of the machine. Power is derived through an ordinary pulley 5 which is fixed on this shaft, as is also a small pulley 6 for driving the feed rollers, a cam 7 for shifting the support for one of the feed rollers, crank arms 8 which are connected by a crank pin 9 for driving a pitman 10, which is connected to the main plunger of the machine, through a pin 11 and cam 12 for driving a part of the feeding mechanism and a crank 13 for driving a pneumatic mechanism connected with the blank feed.

The pitman 10 runs to the pivot pin 11 in a suitable cross head 14 on the plunger 15, and this cross head is mounted to slide freely in a suitable cross head guide 16 that rises from the base 2. The extreme end of the plunger 15 is provided with an expander 17 which consists of a supporting block 18 that has a number of slots therein and in each slot is pivotally mounted an arm 19, which has its outer end pivotally connected to a link 20 which runs to a sliding block 21, where it is pivotally connected, and this block 20 slides on the plunger 15 and is actuated by an arm 22 which is connected thereto and also to a sliding shaft 23 which slides in the direction of its length in suitable guides 24 mounted on the base 2. In the active direction this shaft 23 is moved by a coil spring 25 which has one end fixed to an upright coming from the base 2 and the other end to the shaft, and in the other direction this shaft is moved by the arm 22 which is shoved by the block 20 which in turn is shifted by the block 17 on the end of the plunger 15.

The arms 19 coöperate with corresponding grooves 26 of a die 27, which is held in a suitable support 28 fixed to the base 2. This die 27 is flared substantially as shown and provided with shoulders 29 in the corrugations which prevent the finished article 30 from being withdrawn by the return movement of the plunger 15 and its connected parts. In its extreme front end this die 27 is provided with a suitable guard 31 which is fixed thereto and placed so as to receive and support a blank 32 just before the plunger 15 and its connected parts act on the same. This guard is recessed at 33 to receive the arm 22 at the forward limit of its movement. The rear end of the die 27

is fixed to a suitable sleeve 32, which is large enough to receive and hold about one hundred nested vessels, just after the same have been formed in the die 26. This is to hold 5 the vessels until they have become firmly set and will permanently retain their proper shape. To further facilitate and improve the action of the die, it may be heated by an electric or other heater 33, which surrounds the same and receives an electric current from any suitable source, not shown.

From the sleeve 32, the finished vessels are thrust into a suitable trough 34, which is supported by brackets 35, which rise from 15 the bed 2, or in any other suitable way. This trough is of any desired length and is made long enough to receive any convenient number of complete paper vessels so that an attendant may attend several machines while 20 a number of vessels are accumulating.

In view of the foregoing, it will be understood that the rotation of the shaft 4 causes a rotation of the cranks 8 with a corresponding oscillation of the pitman 10 and reciprocation of the cross head 14 with the attendant movement of the plunger 15, which is fixed thereto. The die 26 is also fixed and placed so as to coöperate with the arms 18 and block 17 on the plunger 15, as above 25 described, so that as this plunger continues its motion, and passes through the die 26, the vessel just made is caught in the die by having its rear edge against the shoulders 28 and thereafter the piston 15, with 30 its connected parts, is withdrawn and a new blank is brought to rest on the guide 29 and the operation is repeated and the second vessel is nested in the first, and this 35 cycle is repeated as long as the machine operates.

The blank 30 is fed automatically to the die in a manner which will now be described, and by mechanism which will be explained.

Rising from the bed 2 are two parallel 45 uprights 36 which at their top carry the inclined table 37 on which the blanks 30 are placed in a pile which is kept properly centered by means of suitable guides 38 which are adjustably mounted on the table 40 and about the center. There is an opening 39 at the center of the table 37 and below 45 this are two inclined guides 40. The blanks in this opening, before they are in motion, are supported on these guides and they 55 guide the lowest blank when its movement is initiated by a mechanism which will be described below.

In the embodiment of my invention herein set forth, the lowest blank is removed 60 after being separated from the rest of the pile. It is separated by means of an air blast directed by a nozzle 41 supported on the lower surface of the table 37 and directed toward the center of the opening 39, 65 at its lowest point. This nozzle 41 is con-

nected to a tube 42 which runs to one end of a cylinder 43 which has a piston sliding therein, which is connected to the rod 44 in the conventional way and this rod 44 runs to the crank 13 on the shaft 4 so 70 that the piston in the cylinder 43 operates in unison with the shaft 4 and the cams and cranks connected therewith. Obviously, the blast of air blown at the edges of the blanks 30, separates them to a slight degree, and while this separation is taking place, the twin suction nozzles 45 (see Figs. 8 and 7) are brought against the lower surface of the lowest blank and then swung downwardly so as to bring this blank with 80 its lower edge nearly vertical and between feed rollers 46 and 47 which are separated until the blank is in place between them, and then these rollers are brought together and feed the blank to its position of rest 85 on the guide 29 where it is operated on, as above described. Suction is obtained for the nozzles 45 by means of a hollow shaft 48, on which they are mounted and this shaft is allowed to oscillate but is so formed 90 that while it oscillates, it has its opening connected to a pipe 49 which runs to the rear end of the cylinder 43, that is the end removed from that to which the tube 42 runs. From this it is obvious that as the piston reciprocates on the piston rod 44, the tube 42 supplies an air blast while the tube 49 supplies an exhaust, and conversely when the tube 42 supplies an exhaust, the tube 49 supplies a blast which acts to separate 100 the nozzles 45 from the blank to which they have been secured. The apparatus is so timed that the blast in the nozzles 45 takes place at the time the feed rollers 46 and 47 press the blank and begin to operate and when they do this, they draw this blank over the guides 40 and force this blank into place on the guide 29, as above described. The shaft 48 is oscillated by means of a crank 50 which is fixed thereto, 110 and pivotally connected to a link 51, which runs to an arm 52, which is pivotally mounted at the top of an upright 53 on the bed 2 and provided with a pintle roller 54 which is adapted to engage the cam 12. 115 This arm 52 is provided with an extension 55, which extends to near the table 2, and at its end, it is provided with a coil spring 56 which connects it with an upright on this table so that under normal conditions, the 120 pintle 54 is kept against the cam 12 at all times so that the shifting of the rod 51 will be governed by the cam. The cam 12 is so shaped that the nozzles 45 are drawn so as to properly discharge their functions 125 as above described.

The feed rollers 46 and 47 rotate continuously and are mounted on suitable parallel shafts 57 and 58 respectively, the former being journaled in the uprights 36 and the 130

latter in a movable frame 59, which is pivotally mounted on pins 60 set in the uprights 36. The shafts 57 and 58 are provided with small pulleys 61 and 62 respectively which are driven by one long belt 63 which runs over the pulley 6 and also over idle pulleys 64, 65 and 66. The two latter pulleys are mounted on a spindle 67 which extends from the frame 36 and the pulley 64 is mounted on a bracket arm 68, which is pivotally mounted on the upright 36 so that at all times the belt 63 has proper tension. It is necessary to provide a tensioning means because of the oscillations of the frame 59, which oscillates by means which will now be described. A link 69 is pivotally connected to this frame 59 near its upper end, or in any other suitable place, and extends to the front of the machine where it is pivotally connected to a short arm 70, which is pivotally connected at its upper end to an upright 71 on the table 2. This arm 70 also carries a pintle 72 which engages the cam 7 on the shaft 4. A spring 73 runs from the upright 71 to a projection 74 fixed to the link 69 so that under all conditions of service, the pintle 72 is held in contact with the cam 7. This cam is so shaped that the frame 59 is swung away from the shaft 57 when the blank is fed as above described, and brought back toward this shaft and kept near this shaft throughout the remainder of the feed of the blank so that the rollers 46 and 47 may properly coöperate. A suitable guard 75 is provided on the frame 59 for preventing the blank from getting caught or injured while passing through the feeding mechanism, as above described.

In view of the foregoing, the operation of my improved machine will be readily understood. A pile of blanks is put in position and the machine is started. A blast of air through the nozzle 46 separates the last blank from its fellows at its forward edge and while this separation occurs the suction through the nozzles 45, holds these nozzles to the lower surface of this blank and then these nozzles are thrown downwardly so as to bend the blank and place its lower end where it gets between the rollers 46 and 47 and release it because of the blast and then these rollers feed the blank to the guide 29, where it comes to rest. The plunger 15, with its attendant mechanism, then acts as above described to force the blank through the die 26 in the proper manner and then the plunger is withdrawn and meanwhile the feeding mechanism has acted so that as soon as the plunger has withdrawn, a

second blank is fed as before and this cycle of operations is repeated indefinitely so that finished vessels, after being kept in a heated condition in the die and sleeve 32 long enough to receive their proper shape 65 and set, enter the trough 34 where they accumulate until removed by the operator and packed.

While I have shown and described one embodiment of my invention, it is obvious 70 that it is not restricted thereto, but is broad enough to cover all structures that come within the scope of the annexed claims.

What I claim is:

1. In a machine of the class described, a 75 plunger, an expander mounted on said plunger, a fixed die adapted to receive said plunger, a shoulder in said die adapted to engage an edge of a vessel formed between the die and plunger and prevent the vessel 80 from returning with the plunger when the same is withdrawn from the die, and means for removing a blank from a pile and feeding it between the die and plunger.

2. In a machine of the class described, a 85 plunger having an expander, and a fixed die having corrugations with notches therein, and means for forcing the plunger and its expander through the die to form a vessel which engages said notches so that the 90 plunger may be withdrawn without withdrawing the vessel.

3. In a machine of the class described, a plunger, an expander mounted thereon, a die open at both ends and provided with 95 corrugations adapted to coöperate with said expander and a heater on said die, whereby the corrugations may be formed under the influences of heat and pressure and one vessel may be packed in another while hot 100 when the machine is in operation.

4. In a machine of the class described, means for feeding one blank at a time, a plunger, an expander mounted thereon, a die with a grooved interior and corruga- 105 tions, and a sleeve secured to said die and adapted to receive a number of vessels made successively by the die and plunger and hold the same securely until the parts become set.

5. In a machine of the class described, a plunger, an expander mounted on said plunger, a cross head for guiding said plunger and a guide in which said cross head is mounted, a main shaft and means 115 for driving said plunger from said main shaft, a fixed die held in operative relation to said plunger and means for feeding one blank at a time between the die and plunger.

HARRIET HILL.
